UNITED STATES PATENT OFFICE.

GEORGE W. SMITH, JR., OF RIVERTON, NEW JERSEY, ASSIGNOR TO VICTOR TALKING MACHINE COMPANY, A CORPORATION OF NEW JERSEY.

SOUND-REPRODUCING MEANS.

Application filed February 25, 1925. Serial No. 11,543.

This invention relates to a combined talking machine and radio receiving apparatus, and more particularly to a combination device of this character which is adapted to be installed in an upright cabinet.

Difficulty has been experienced heretofore in mounting a radio receiving apparatus in a talking machine cabinet without materially changing the size and shape of the latter. 10 It has been proposed to use the record storage compartment of such a cabinet as a chamber for the radio receiving apparatus, but this is not satisfactory, since it requires the provision of additional means for storing the record tablets. If the usual record storage chamber is retained, the additional space for the radio apparatus could only be provided by increasing the size of the cabinet, but such an increase in size, if unac- 15 companied by a change in shape, resulted in a cabinet of unpleasing appearance and undue bulk.

In order to combine the two instruments in an upright cabinet and at the same time 20 provide for sufficient record storage space, it has been proposed to mount the radio apparatus in the hinged lid employed for closing the tone-arm and turn table compartment. Such an arrangement is unsatisfactory, since accidental closing of the lid may result in serious damage to the delicate 25 radio instruments, while difficulty has been experienced in opening and closing the lid due to the weight of the radio apparatus. Furthermore, the size of the lid must be materially increased, and the radio apparatus is inaccessible for inspection and repair.

An object of the present invention is to 30 provide a talking machine cabinet having a radio apparatus as well as sound reproducing mechanism mounted therein which overcomes the above difficulties.

Another object of the invention is to provide a combination device of this character 35 wherein the means for mechanically reproducing the records can be used for changing electrical vibrations into sound waves having the amplitude of those generated by the usual loud speaker.

One form which the inventive idea may 40 assume is shown in the accompanying drawings, which drawings, however, are for the purpose of illustration only and are not to be taken as defining the limits of the inven-

tion, reference being had to the appended 55 claims for this purpose.

In the drawings, Fig. 1 is a front elevation illustrating one embodiment of the inventive idea;

Fig. 2 is a top plan view partly in section 60 illustrating one form of means which may be employed as a mechanical reproducer and loud speaker, the device being shown in the position it occupies when the lid of the cabinet is closed;

Figs. 3, 4, and 5 are enlarged detail sectional views of one type of mounting which 65 may be employed for the combined reproducer and loud speaker;

Fig. 6 is a rear elevation of a cabinet that 70 may be employed for housing the instruments;

Fig. 7 is a sectional view taken on the line 7-7 of Fig. 6; and

Fig. 8 is a section taken on the line 8-8 75 of Fig. 6.

Referring to the drawings, wherein like reference characters refer to like parts throughout the several views, 1 is an upright talking machine cabinet that is provided with the usual hinged lid 2 and lid support 3. The lower portion of the cabinet is formed to provide a record storage compartment 4 of any suitable character. If desired, this storage space may be provided 80 with the usual hinged doors 5. Positioned in the cabinet space above the record storage space 4, and in the space ordinarily occupied by the volume amplifier or horn, is a radio receiving apparatus of any suitable character and mounted in any suitable way. In the form shown a slidably mounted panel 6, that is preferably inclined from the vertical, carries the control members 7 of the radio receiving apparatus, but it is to be expressly understood that any other suitable 85 mounting for said panel may be provided. The construction of the panel 6 and the manner in which it is slidably mounted in the cabinet may be such as is disclosed in detail in the co-pending application of Armour P. Luker, Serial No. 10,675, filed Feb. 20, 1925, and forms no part of the present invention. Hinged closure members 8 are shown for closing the space or compartment 90 occupied by the radio receiving apparatus.

In conformity with the present invention suitable means are employed for reproduc-

ing the record tablets, said means being so constructed as to render the need for the usual enclosed volume amplifier or horn unnecessary. At the same time, said reproducing instrument is preferably so constructed as to be adapted for use as a radio loud speaker.

In the form shown, the mechanical reproducer and loud speaker structure comprises a supporting bracket 9 which is secured in any convenient manner to the upper surface of the talking machine motor board 10. The bracket 9 is provided with suitably spaced pivot members which in the present instance comprise a ball 11 fitted in a pocket 12 formed in the bracket to constitute a lower pivot support, and a pin 13 which is slidably mounted in the upper portion of the bracket and provided with a conical portion 13^a on the lower end thereof to constitute an upper pivot member. A set screw 14 is threaded into the bracket 9 in such a position as to engage the pin 13 and secure the latter in any position to which it may be adjusted.

Supported between the elements 11 and 13 is an arm 15 which preferably comprises a hollow inner portion 15^a that is maintained in operative engagement with a hollow outer portion 15^b by means of a bolt 16 extending through registering openings in said portions. Longitudinal movement of the outer supporting arm portion 15^b along the bolt 16 is prevented by means of a threaded member 17 which extends through the wall of said portion and into a transverse recess or hole 16^a in the bolt 16. If desired, the inner end of the bolt 16 may be threaded as at 16^b to receive a lock washer 18 and locking nuts 19, which may be adjusted to bear with any desired pressure against the inner side of the arm portion 15^a.

The outer end of arm portion 15^b is bifurcated to receive two horizontal adjustable pivot pins 20 and 20^a, which latter constitute supporting means for a swinging arm 21. The latter is shown as provided with an arcuate portion 21^a from the opposite ends of which extend converging radial arms 21^b that are joined together at their inner ends by a circular portion 21^c. A large diaphragm 22 of any suitable construction, and shown as of the pleated type, is supported by a spider 23 and attached in any desired manner to the circular portion 21^c of the swinging arm 21. This diaphragm is provided with the usual stylus bar 24, stylus bar mounting 25 and stylus 26. A radially extended tab 27 is preferably provided at any convenient point on the periphery of the diaphragm spider 23 to manipulate the same in a manner to be described.

If desired, the diaphragm may be additionally supported from the swinging arm 21 by the connections indicated at 28 and 28^a

in Fig. 2. As shown more clearly in Figs. 3 and 4, these connecting means comprise screws 29 passing through the periphery of the spider 23 and having threaded engagement with the swinging arm 21. Spacing members 30 on said screws 29 may be interposed between the swinging arm and the periphery of the spider 23 if desired.

Resilient means are preferably provided between the swinging arm 21 and the supporting arm portion 15^b in order to prevent the stylus from receiving the entire weight of the swinging arm and the elements supported thereby. In the form shown this means comprises a spring 31 which is positioned in the outer end of the longitudinal opening extending through the arm portion 15^b. The inner end of spring 31 bears against the outer end of the bolt 16 while the outer end of this spring has engagement with a sliding pin 32 which projects outwardly from said opening into engagement with a lug 21^d formed on the swinging arm 21. If desired, an adjusting member 33 may be threaded into the lug 21^d in position to engage the sliding pin 32.

When reproducing a record tablet the diaphragm and its supporting structure occupy a substantially vertical position as illustrated in Figs. 1, 3, and 4, and means must be provided for maintaining the diaphragm in said vertical reproducing position. Various means may be employed for performing this function; in the form shown, an L-shaped latch member 35 is pivotally secured to the inner arm portion 15^a, by means of a horizontally disposed pin 34, and is normally maintained with its lower arm 35^a in a horizontal position by means of a spring 36 positioned in a recess in arm portion 15^a and bearing against the upper arm 35^b of the latch member. As shown in Figs. 3, 4, and 5 the diaphragm is locked in vertical position when the lower arm 35^a of said latch member extends into a recess 37 formed in the inner end of the outer arm portion 15^b. The arm 35^a is also adapted to engage a second recess 38 formed in the arm portion 15^b at an angular distance of 90° from the recess 37 when the diaphragm and its supporting structure are moved to a horizontal, inoperative position, as shown in Fig. 2.

In order that access may be readily had to the rear of the radio receiving apparatus for making the necessary connections to ground, antenna, batteries, etc., the cabinet may be provided with a removable panel as is illustrated in Figs. 6, 7, and 8. As here shown, the rear wall of the cabinet is formed by a removable panel 39 which is retained in position at its upper end by means of a loosely fitted tongue and groove connection 40, and is secured at its lower end by means of bolts 41 which extend through the panel 130

and have threaded engagement with the upper arms of L-shaped brackets 42 that are rigidly attached at any desired point to the cabinet framework. The various wires (not shown) which lead from the radio receiving apparatus, may pass through an aperture 43 in the cabinet partition wall 44 and through an opening or openings 45 provided in the lower cabinet partition 46 below the record storage space. Preferably the shelves illustrated in space 4 for supporting the records do not extend to the rear wall of the cabinet, but terminate at a suitable distance in front of this wall to provide a compartment 47, 15 between the inner ends of the shelves and the panel 39, to which access is had by means of said removable panel 39. A partition wall 48 parallel to the removable panel 39 may be provided to support the inner ends 20 of the shelves and complete the compartment 47, and some or all of the batteries of the radio apparatus may be stored in this compartment. If desired, a sliding drawer 49 may also be provided in any suitable 25 manner below the lower partition wall 46 for receiving batteries employed in connection with the radio receiving apparatus, although this is not necessary.

It is desirable that the diaphragm employed in mechanically reproducing the records also serves as a loud speaker for the radio apparatus. To this end there is mounted in the motor board 10, and adjacent the turn table, a device 50 of any suitable 35 type for converting electrical vibrations into mechanical vibrations, and by which the diaphragm is set into vibration when the stylus 26 is engaged therewith.

When the diaphragm is in the position illustrated in Fig. 1 and it is desired to reproduce a record tablet, the operator may readily move the stylus into engagement with said tablet by grasping the radially extending tab 27 and moving the device as required about the pivot members 20-20^a and 11-13. Because of the character of the diaphragm employed no amplifying horn is required. If it is desired to operate the radio receiving apparatus, the diaphragm and its 50 associated elements are moved to bring the stylus 26 into engagement with the converting device 50 in a manner which is well understood in the art.

When the machine is not in use and it is desired to close the lid 2, the diaphragm is moved upwardly about the horizontal pivots 20-20^a to force the extending portion 21^a of the swinging arm 21 into engagement with the upper arm 35^b of the L-shaped latch 35. This engagement forces the arm 35^b to the left as viewed in Fig. 3, against the tension of spring 36, and the arm 35^a is disengaged from the notch 37. The diaphragm and its associated elements may now be rotated to the left until the recess 38 in portion

15^b is brought into alignment with the arm 35^a whereupon spring 36 forces arm 35^a into said recess 38 and the diaphragm and its associated elements are locked in horizontal position as shown in Fig. 2. The lid 2 may now be closed.

While the sound reproducing instrument has been illustrated and described with considerable detail in order to fully disclose one operative embodiment of the present invention, it is to be understood that any other suitable form of reproducing instrument may be employed and that the details of this instrument and its mounting per se constitute no part of the present invention except as a part of the larger combination.

It will therefore be perceived that the present invention enables the use of a talking machine cabinet, particularly of the upright type, of the size and shape heretofore employed as a housing for radio apparatus without subtracting any of the functions heretofore obtained by the use of said cabinets. By employing a talking machine including reproducing mechanism of the hornless type, the full volume of sound heretofore obtained by the use of an enclosed amplifier or horn can be secured, while the compartment heretofore employed for the housing of said amplifier or horn can be given over to the storage of the radio apparatus.

While the present invention is applicable to talking machine cabinets not provided with a record storage space, and such a construction is to be understood as included in the present invention, the invention provides for retaining the record storage space in cabinets of the type heretofore including such a compartment. The sound reproducing mechanism of the talking machine is disposed entirely above the motor board, or the compartment heretofore employed for housing the sound amplifier or horn and is preferably, housed in a compartment formed by a cover when closed. The reproducing mechanism can be folded or moved into an inoperative position and must be moved to a different position to be rendered operative.

While the present invention is particularly useful to enable radio apparatus to be combined with talking machine mechanism in upright talking machine cabinets of the shape and size heretofore employed, the present invention enables radio apparatus to be combined with talking machine mechanism in other forms of cabinets without increasing the size, shape or bulk of the cabinet, and the present invention in its broadest aspects is therefore not limited to talking machine cabinets of the upright type.

While only one embodiment of the invention has been illustrated, various changes, some of which will now readily occur to

those skilled in the art, may be made in the details of construction and arrangement without departing from the invention as defined in the appended claims.

5. What is claimed is:

1. A device of the class described comprising, in combination, a talking machine cabinet having a motor board adjacent the top of said cabinet and talking machine mechanism therein, a hinged cover forming with the walls of said cabinet and said board a compartment above said motor board, reproducing mechanism of the hornless type in said compartment and including a large sized diaphragm adapted to be moved to an inoperative position in which it is housed within said compartment or to a playing position at an angle thereto when the cover is raised, radio receiving apparatus in said cabinet, and means carried by said motor board for employing said reproducing mechanism as the loud speaker of said radio apparatus.
2. A device of the class described comprising, in combination, an upright talking machine cabinet having a motor board and talking machine mechanism therein, a hinged cover for the cabinet forming with the walls of the cabinet and said motor board a relatively shallow compartment of the

character heretofore provided in talking machine cabinets for housing reproducing mechanism of the tone arm type, sound reproducing mechanism of the hornless type carried by said cabinet within said compartment, radio apparatus in said cabinet, and means for operatively connecting said radio apparatus with said reproducing means. 35

3. A device of the class described comprising, in combination, a talking machine 40 cabinet having a motor board and talking machine mechanism therein, sound reproducing mechanism of the hornless type including a large sized diaphragm mounted on said board, a hinged cover for said cabinet forming with the latter and with said board a compartment for housing said reproducing mechanism, means mounting said reproducing mechanism whereby it may be moved to an inoperative position substantially parallel to said cover or to a substantially vertical operative position, radio receiving apparatus mounted in the cabinet below said motor board, and means carried by the latter for operatively connecting 50 55 said reproducing mechanism with said radio apparatus.

In testimony whereof I have signed this specification.

GEORGE W. SMITH, JR.
